UNITED STATES PATENT OFFICE.

EDDIE BRYAN BLACK, OF COMMERCE, GEORGIA.

CONVERTIBLE SWING.

1,335,360.

Specification of Letters Patent. Patented Mar. 30, 1920.

Application filed November 13, 1919. Serial No. 337,739.

To all whom it may concern:

Be it known that I, EDDIE BRYAN BLACK, a citizen of the United States, and a resident of Commerce, in the county of Jackson and 5 State of Georgia, have invented certain new and useful Improvements in Convertible Swings, of which the following is a specification.

My invention is an improvement in convertible swings, and has for its object to 10 provide a swing of the character specified, which may be easily converted into a hammock or reclining swing.

In the drawings: 15 Figure 1 is a front view of the improved swing,

Fig. 2 is an end view,

Fig. 3 is a vertical section,

Fig. 4 is an end view, showing the swing 20 converted into a hammock.

In the present embodiment of the invention the improved swing comprises a supporting frame, composed of two longitudinally extending plates 1 and 2, which 25 support near their ends, ends 3 for the swing, and the said ends are connected by a bottom frame 4, the bottom frame resting on the plates 1 and 2. A back 5 is provided, the said back being secured to the end pieces 30 and to the plate 2 and to the bottom frame 4, and the back may be of any suitable character, in the present instance an open frame, is inclined with respect to the bottom frame as shown. The end frames of 35 the swing have arm rests as shown, and these arm rests extend beyond the front of the swing as shown in Figs. 2 and 3. Supporting chains 6 are provided for the swing, the said chains being adapted to engage 40 hooks and each chain has at the end adjacent to the swing branches 8, 9 and 10 which are connected with the plate 1, and with the back and the plate 2 respectively. In the present instance the branch 10 extends from 45 the branch 9, and they are connected to the swing in any suitable or desired manner.

A cushion seat 11 is arranged on the bottom frame, the said seat resting at its center on a bar 12 which extends longitudinally 50 of the bottom or seat frame, and this seat cushion may be of any desired material that is suitable for the purpose. Referring to Fig. 1 it will be seen that the bar 12 extends well beyond the bottom frame at each end, 55 and it supports the central portion of the cushion elevated, so that the cushion as a

whole is convex from front to rear. The upper end of the back is formed by a plate 13 which is detachably connected with the side members of the back and a strip 14 of 60 flexible material, which fills in the frame of the back when the device is used as a swing is connected at one end to this plate 13, in any suitable manner, as for instance by folding the said end about the plate and 65 securing it thereto. At its other end this strip 14 has a loop 15 which engages about the cushion 11 and a cross bar 16 which extends longitudinally of the bottom frame 4 at the front thereof. This strip is of sufficient 70 length, such that when the plate 13 is detached from the back frame in a manner to be presently described and extended as shown in Fig. 4, the strip will have sufficient length 75 to form a hammock. When the device is in use as a swing the strip 14 is lapped about the plate 13 to take up slack.

The plate 13 is detachably held to the back frame 5, in any suitable manner, as for instance by bolts 17 which are mounted to 80 slide in guide plates 18 on the ends of the back frame. These bolts engage staples 19 on the forward edges of the plate 13, and the staples pass through slots in the plates 18 which lap upon the forward edges 85 of the plate 13 when the plate 13 is in place on the back frame, thus locking the plate in place on the back frame, when the device is used as a swing. All of the strain on the plate 13 when the device is in use as a 90 swing, and there is very little strain on the said plate, tends to draw it toward the back frame, so that it is not difficult to hold it in place. This plate 13 is provided with 95 eyes 20 near its ends, which are adapted to be engaged by chains 21 to support the device in the manner shown in Fig. 4. Referring to Fig. 1 it will be seen that the plate 13 is long enough to extend well beyond the end frame when it is in place. 100

In use, when the device is arranged as shown in Fig. 3, it makes a very comfortable swing or seat. The excess length of the strip 14 is wrapped about the plate 13. When it is desired to extend the device into 105 a hammock, the plate 13 is detached from the end frame, and is connected with the chains 21. The device is now a comfortable hammock, the seat cushion serving as a pillow. Referring to Fig. 1 it will be seen that 110 the chains 8 and 10 are connected to the plates 1 and 2 by means of bolts 22. The

- edge of the plates 1 and 2 is slotted at its ends to permit the passage of a link of the chain, and the bolt moves in staples 23 which are arranged on opposite sides of the slot. When the chain has been inserted through the slot, the bolt is pushed into place, thus firmly locking the chain. The branches 9 are connected with eyes 24 on the ends of the back frame.
- 10 It is to be understood that the improved swing may be constructed of any desired or approved material, may be of any desired dimensions and shape in accordance with conditions. The essential feature of the invention is the detachable plate to which one end of the flexible strip is connected, being connected at the other end to the cushion and hinging the cushion to the seat frame at the forward end of the frame, so that 20 when the strip is extended it will form a hammock.

I claim:

1. In combination, a seat frame, a cushion for the frame, a plate extending longitudinally of the seat frame at the top and back thereof, means for detachably connecting said plate to the frame, a flexible strip connected at one end to the plate and at the

other to the seat and forming the back of the seat frame, and having a portion winding upon the plate when the plate is in place on the frame and adapted to be extended when the plate is removed to form a hammock, said cushion being hinged to the seat frame at the forward edge of the cushion, means for suspending the seat frame, said means being detachable from the rear of the seat frame for the purpose specified.

2. In combination, a seat frame, a cushion for the frame, a plate extending longitudinally of the seat frame at the top and back thereof, means for detachably connecting said plate to the frame, a flexible strip connected at one end to the plate and at the other to the seat and forming the back of the seat frame and having a portion winding upon the plate when the plate is in place on the frame and adapted to be extended when the plate is removed to form a hammock, said cushion being hinged to the seat frame at the forward edge of the cushion.

EDDIE BRYAN BLACK.
